(57) CLAIM

The ornamental design for a face mask, as shown and described.

DESCRIPTION

FIG. 1 is a front, right and top perspective view of a face mask showing our new design;

FIG. 2 is a rear, left side, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines that form a closed planar shape in the central area shown in FIG. 8 are only for the purpose of illustrating a neck opening in the face mask and do not form any part of the claimed design; all other broken lines illustrate stitching and form part of the claimed design.
